(57) CLAIM

The ornamental design for a hood hat, as shown and described.

DESCRIPTION

FIG. 1 is a perspective view of a hood hat of the present invention;

FIG. 2 is a front view thereof;

FIG. 3 is a back view thereof;

FIG. 4 is a side view thereof;

FIG. 5 is another side view thereof;

FIG. 6 is a top plan view thereof;

FIG. 7 is a bottom plan view thereof; and,

FIG. 8 is a cross-sectional view taken along line 8-8 in FIG. 2.

The broken lines shown in the drawings depict portions of the hood hat that forms no part of the claimed design. The broken lines showing environment and the human face forms not part of the claimed design.
